UNITED STATES PATENT OFFICE.

PAUL C. DELAIZE, OF NEW YORK, N. Y.

DESIGN FOR A BOX OR SIMILAR CONTAINER.

Application filed January 26, 1927. Serial No. 20,494. Term of patent 7 years.

To all whom it may concern:

Be it known that I, PAUL C. DELAIZE, a citizen of France, residing at New York, in the county and State of New York, have invented a new, original, and ornamental Design for Boxes or Similar Containers, of which the following is a specification, reference being had to the accompanying drawing, forming part thereof.

I claim:

The ornamental design for a box or similar container as shown.

PAUL C. DELAIZE.
